UNITED STATES PATENT OFFICE.

MARYAN JASZEWSKI, OF BETHLEHEM, PENNSYLVANIA.

DESIGN FOR A CURTAIN-POLE HOLDER.

56,005.

Specification for Design.

Patented Aug. 10, 1920.

Application filed October 27, 1919. Serial No. 333,847. Term of patent 7 years.

To all whom it may concern:

Be it known that I, MARYAN JASZEWSKI, a citizen of Poland, residing at Bethlehem, in the county of Northampton and State of Pennsylvania, have invented a new, original, and ornamental Design for a Curtain-Pole Holder, of which the following is a specification, reference being had to the accompanying drawing, forming part thereof.

The figure is a view in perspective of a curtain pole holder, showing my new design.

I claim:

The ornamental design for a curtain pole holder, as shown.

MARYAN JASZEWSKI.
